UNITED STATES PATENT OFFICE.

JOHN D. TAYLOR, OF BUFFALO, NEW YORK, ASSIGNOR TO TAYLOR SIGNAL COMPANY, OF BUFFALO, NEW YORK, A CORPORATION OF NEW YORK.

RAILWAY SWITCHING AND SIGNAL INTERLOCKING APPARATUS.

SPECIFICATION forming part of Letters Patent No. 707,181, dated August 19, 1902.

Application filed November 10, 1900. Serial No. 36,020. (No model.)

To all whom it may concern:

Be it known that I, JOHN D. TAYLOR, a citizen of the United States, residing at Buffalo, New York, have invented certain new and 5 useful Improvements in Railway Switching and Signal Interlocking Apparatus, of which the following is a full, clear, and exact description.

This improvement is used with and relates 10 to railway signaling and switching apparatus operated and controlled by electricity, and, further, is an improvement upon the system and apparatus disclosed in my former patents, No. 554,097, February 4, 1896, and No. 15 605,359, June 7, 1898, and in my pending application, filed November 10, 1900, Serial No. 36,022.

The object of this invention is to secure a 20 more certain and perfect indication of the movement of a switch or signal and release of the locking mechanism between a lever controlling a particular switch or signal and levers controlling other switches or signals governing routes conflicting with the route 25 governed by said particular switch or signal in its position previous to the movement. As this release is effected through the movement of a piece by the current generated in the case of a switch by the rotation of the motor-armature after the switch has been moved 30 home and locked in either position and in the case of a signal by the rotation of the motor-armature in the last part of the movement when the signal is going to the "normal" 35 or danger position, and as the currents so generated are of only momentary duration it is desirable to have the mechanism so constructed that the piece to be moved by the magnetism produced by the current so generated cannot be bound or held by the operator 40 in attempting to move a conflicting lever before the current has had time to act.

Referring to the drawings herewith, in 45 which like characters of reference indicate like parts, Figure 1 is an elevation showing the locking bars and tappets. Fig. 2 is a transverse vertical section. Fig. 3 is a similar view showing the mechanism in a normal position. Fig. 4 is a section on the line $\alpha\alpha$ 50 of Fig. 2 looking in the direction indicated by the arrows. Fig. 5 is a view similar to Fig.

2, showing a signal mechanism, as hereinafter described. Fig. 6 is a diagram of the electric circuits employed in connection with the apparatus herein described. The switch and 55 signal operating machines which form part of and are controlled and operated through the said electric circuits are fully described and illustrated in my patents numbered 516,903 and 554,097.

In Fig. 1 I have shown a portion of a set of locking bars and tappets which are of well-known construction and require no further description.

1 is an electric switch consisting of two single-pole two-throw electric switches mechanically connected. This switch 1 is immediately connected to and operated by the bar 2. The bar 2, which corresponds to the lever in a mechanical interlocking machine having a 70 handle (not shown) attached for moving it, is held between guide-plates 3. It is supported on rollers 4, pivoted to the guide-plates 22 and prevented from upward movement by straps 5 across the guide-plates. It is thus 75 permitted to move only longitudinally. The bar 2 has a slot 6 cut through it, the middle and longest part of which is parallel to the length of the bar. The two parts of the slot 80 contiguous to the middle part are inclined at an angle to the length of the bar and are of equal lengths and inclined at equal angles and in the same direction, and the two parts constituting the ends of the slot are parallel to the length of the bar.

A locking-tappet 7 has a jaw 8 rigidly attached, and a roller 9 is pivoted in the jaw. The jaw 8 is guided by vertical grooves in the guide-plates 3. The roller 9 runs in the slot 6 in the bar 2. When the bar 2 is moved, the tappet 7 remains stationary while the roller 9 is traveling along the parts of the slot parallel to the length of the bar 2 and is moved up or down when the roller 9 travels along the inclined portions of the slot, the direction 95 of movement depending upon the direction of movement of the bar 2. The tappet 7 is locked or released by other similar tappets connected to other levers by the well-known means employed for this purpose in other and 100 well-known forms of interlocking apparatus.

I am aware that the movement of the tap-

tappet 7 by means of the slot 6 has been used and do not claim it except in combination with my invention.

A bar 10 is pivoted in a lug 11, extending 5 downward from the bar 2 and is supported by the armature 12 of the two solenoids 13 and 14, consisting each of two spools. The cores 15 pass through the armature 12 and extend to a considerable distance into both 10 solenoids. They form the support of the armature 12 and with it are free to move a limited distance in the direction of the axes of the coils 13 and 14, which are parallel to the bar 2. The bar 10 has notches with beveled 15 ends 16 and 17 cut into its under surface in such location that in certain positions of the bar 10 and armature 12 the armature may be under the notches 16 or 17. A lug 18, extending upwardly, is formed on the end of the bar 20 10, and when the armature 12 is under a full part of the bar 10 the lug 18 extends into a notch 19, cut in the under side of the bar 20. The bar 20 is capable of a limited longitudinal movement and is held laterally by the 25 guide-plates 3, rollers 21 above, and the frame to which the guide-plates 3 are attached beneath. The movement of the bar 20 is limited by the shoulders of the notch 22, cut in its under surface, abutting against the block 30 23, which bridges across the space between the two guide-plates 3, which contain the bar 20. The circuit-controlling switch 1 is connected to the outer end of the bar 20 and is moved by it. The extent of the movement 35 of the bar 20 is less than the middle horizontal part of the slot 6 in the bar 2 by as much as the notch 19 is larger than the lug 18.

In Fig. 3 the mechanism is shown in the normal position. To reverse it, the bar 2 40 must be drawn out. The part of the movement which carries the roller 9 up the first incline in the slot 6 raises the tappet 7 so as to lock all levers governing routes conflicting with the "reverse" position of the bar or lever 2. At the same time the full part of the 45 bar 10 climbs the end of the armature 12, and the lug 18 is inserted in the notch 19 of the bar 20. The further movement of the bar 2, during which the roller 9 travels along the 50 middle horizontal part of the slot 6, carries the bar 20 along with it, the full part of the bar 10 remaining over the armature 12 during this movement. At the end of this movement the bar 2 is stopped through the bar 10, 55 the lug 18, the notch 19, and the bar 20 by the shoulder of the notch 22 striking the block 23. Here it is held until the current generated by the switch-motor energizes the solenoid 14 and draws the armature 12 under the 60 notch 17 in the bar 10. This allows the bar 10 to drop, withdrawing the lug 18 from the notch 19, after which the bar 2 is free to move the remainder of its stroke, carrying the roller 9 up the second incline in the slot 6. This 65 last movement further raises the tappet 7, thereby releasing other levers to take positions not conflicting with the reverse position

of the bar 2. In putting the bar 2 back into the normal position again the operations are the same except in the reverse direction, and 70 the release comes through solenoid 13 instead of 14 being energized. Fig. 2 shows the mechanism in the relative position in the movement of the bar 2 toward the normal position just before the "indication" or release is 75 given. If the indication-current should from any cause fail to be given, the bar 2 could not complete its movement to release the locking of the other levers; but if the operator should pull the bar 2 back toward its reverse 80 position the armature 12 would in such case be in the proper position to permit the lug 18 to drop out of the notch 19, and so allow the bar 2 to complete its movement whether any 85 current were sent through the solenoid 14 or not. The same conditions would obtain in an attempt to pass from the normal to the reverse position in the event of failure of the indication-current. To prevent a failure of indication of this kind, a lug 24 projects from 90 the side of the armature 12 in the path of a pawl 25, pivoted to the side of the bar 10. As the bar 10 moves the pawl 25 carries the armature 12 with it and keeps it under the full part of the bar 10. Just before the bar 10 is 95 stopped by the shoulder of the notch 22 in the bar 20 striking the stop 23 the point of the pawl 25 is raised above the lug 24 by a lug 26, attached to and projecting downwardly from the guide-plate 3, striking an upwardly-projecting 100 lug 27 at the farther end of the pawl 25. The pawl 25 out of the way, the armature 12 is then free to respond to the current in the solenoid 14. The upper side of the pawl 25 is 105 shouldered near its point, so that when passing under the lug 26 the point of the pawl 25 is depressed so that it cannot miss the lug 24 on the armature 12. A similar pawl 28 is located on the other side of the armature 12 to move it in the opposite direction. These 110 pawls 25 and 28 are provided, respectively, with stops 29 and 30 to prevent their points dropping too low. The pawls come into action only in case of a failure of the indication-current on a previous movement. In order 115 to prevent a rebound of the armature 12 when it is quickly moved, which might result in a false indication, I provide an additional lock, which is described below. The lower end of the armature 12 is made V-shaped, and held 120 against it by means of a spring 33 is a bolt 31, having an oppositely V-shaped head. The bolt 31 is contained within and guided by a chamber 32, attached in any suitable manner to the frame of the solenoid. The spring 33 125 is contained within the chamber 32 between the head of the bolt 31 and the bottom of the chamber. The armature 12 in passing from either position to the other depresses the bolt 31, thereby compressing the spring 33, and 130 the force required to effect this compression is sufficient to prevent the rebound of the armature 12 when it is suddenly thrown by a too-rapid movement of the bar 2.

The signal-lever apparatus, as shown in Fig. 5, is similar to the switch-lever apparatus, except that as indication is required only when going to the normal or danger position only one pair of solenoids 13^a, one pawl 28^a, and one notch 16^a in the bar 10^a are provided. To permit the signal-lever to make its complete movement in the reverse direction without indication, the notch 19^a is made longer. In its movement to the normal position it is exactly like the switch-lever, and the same description answers for both. To more fully describe the functions of this apparatus, I will trace the electric circuits by means of which the electric power is transmitted to the switch and signal operating machines from the primary source and from the switch and signal operating motors to the indicating and releasing mechanism forming part of the herein-described apparatus. For this purpose reference will be made principally to Fig. 6.

Reversing or drawing out the bar 2 moves the electric switch comprising the bars 1 and 1^a so that the bar 1 breaks connection with the contact 60 and makes connection with the contact 58 and the bar 1^a breaks connection with the contact 61 and makes connection with the contact 59. The bar 1^a of the electric switch and the contacts 59 and 61 are not shown in Figs. 2 and 3, because they are directly behind the corresponding parts 1, 58, and 60. This new position of the electric switch 1 and 1^a closes a circuit of the battery 34, so that current flows from the battery 34 through the wires 35, 36, and 56, contact 58, bar 1, wire 81, contact 65, bar 67, wire 69, armature 70 of switch-operating motor, wire 71, bar 68, contact 66, wire 73, field-coils 74 of said motor, wires 75 and 52 back to the battery 34. This current causes the rotation of the armature 70 and through the gearing connecting it with the switch-rails effects the movement of the track-switch from the normal to the reverse position, as fully described in my said patents. Near the end of this movement the electric switch consisting of the bars 67 and 68 and the contacts 63, 64, 65, and 66 and which is automatically operated by the switch-operating mechanism is reversed or changed in position, so that the bar 67 breaks connection with the contact 65 and makes connection with the contact 64 and the bar 68 breaks connection with the contact 66 and makes connection with the contact 63. This closes a circuit including the switch-operating motor and the solenoid 14, so that the current generated by the rotation of the armature 70 due to momentum flows from said armature through wire 69, bar 67, contact 64, wires 72 and 73, field-coils 74, wires 75, 52, 55, 80, and 79, solenoid 14, wire 76, contact 59, bar 1^a, wire 62, contact 63, bar 68, and wire 71 back to the armature 70. This current is in the proper direction through the field-coils 74 to build up the

magnetization of the field-magnets, and it energizes the solenoid 14, causing it to move the armature 12, and releases the bar 10, as before described. From this it can be easily seen that replacing the switches 1 and 1^a into the normal position will repeat the operation except in the reverse direction and that the solenoid 13 comes into play instead of the solenoid 14. When the track-switch is in the proper position to reverse or clear the signal, the electric-switch arm 41, which is connected mechanically to the track-switch and moves with it, is in position to make electrical connection between the contacts 40 and 42. The electric switch 1^b, Fig. 6, is the same in construction and mechanical connection as that shown at 1, Figs. 2 and 3. When the signal-controlling bar 2 is reversed, the electric-switch bar 1^b, through the mechanical connections before described, is changed in position so that it breaks connection with the contact 54 and makes connection with the contact 38, thus closing a circuit of the battery 34, so that the current flows from said battery through the wires 35 and 37, contact 38, bar 1^b, wire 39, contact 40, bar 41, contact 42, wire 43, armature 44 of the signal-operating motor, field-coils 45 of the said motor, wire 47, brush 49, rotary switch-arm 50, wires 82, 51, and 52 back to the battery 34. This causes the armature 44 to rotate and through the intermediate gearing draws the signal-blade to clear position and raises the counterweight. The rotation continues until the rotary switch-arm, which is mechanically connected to and moved by the signal mechanism, is separated from the brush 49. This break in the circuit is then shunted by the brake-magnet 46, the current continuing from the motor field-coils 45 through the magnet 46, wires 48, 51, and 52 back to the battery. This energizes the magnet 46, which sets the brake and holds the signal in the clear position so long as the current is maintained, as described in my Patent No. 516,903. When the electric switch 1^b is put back into normal position, it is separated from the contact 38 and put into connection with the contact 54. The circuit above named is thereby broken, and the signal is released to return to normal under the influence of a counterweight. The descending counterweight transmits its motion through the intermediate gearing and causes the armature 44 to rotate in a direction opposite to its direction when driven by the current. When the rotary switch-arm 50 moves far enough to again make contact with the brush 49, a circuit is formed, including the signal-operating motor and the solenoid 13^a, so that the current induced in the armature by its rotation in a magnetic field flows from the said armature through the field-coils 45, wire 47, brush 49, rotary switch-arm 50, wires 82, 51, 52, 55, solenoid 13^a, wire 53, contact 54, bar 1^b, wire 39, contact 40, bar 41, contact 42, and wire 43 back to armature

44. This energizes the solenoid 13^a, causing it to move the armature 12^a so as to release the bar 10^a, as before mentioned.

Having thus described my invention and 5 its method of operation, what I claim is—

1. The combination of an electric switch and a lever-bar actuating the same, consisting of a bar pivoted to said switch, a bar pivoted to said lever-bar, means for engaging said 10 bars and means for throwing said bars in and out of engagement consisting of a solenoid and an armature actuated thereby, substantially as and for the purposes set forth.

2. The combination of an electric switch 15 and a lever-bar actuating the same, consisting of a bar pivoted to said switch, a bar pivoted to said lever-bar, a solenoid energized by the indication-current of the system, an armature actuated by said solenoid, beveled 20 notches in said bar pivoted to said lever-bar which take over said armature, a lug on said bar pivoted to said switch, said bar pivoted to said lever-bar being normally out of engagement with said bar pivoted to said switch 25 and thrown into engagement by carrying a full part of said bar over said armature and finally thrown out of engagement by said solenoid carrying said armature under one of said beveled notches, substantially as and 30 for the purposes set forth.

3. In combination with an interlocking mechanism, an electric switch, a lever-bar actuating the same, means for effecting the movement of one member of said interlocking mechanism by the movement of said lever-bar, locking the other connected members of said interlocking mechanism, a bar pivoted to said lever-bar, a bar pivoted to 35 said switch, a solenoid energized by the indication-current of the system, an armature actuated by said solenoid, beveled notches in said bar pivoted to said lever-bar which engage over said armature, a lug on said bar engaging in a notch in said bar pivoted to said 40 switch, said bars being normally out of engagement and thrown into engagement by carrying a full part of said bar having said beveled notches over said armature, and finally thrown out of engagement by said solenoid carrying said armature under one of 45 said beveled notches, permitting the final throw of said lever-bar, and means for producing the final throw of said member of said interlocking mechanism by the final throw of 50 said lever-bar, substantially as and for the purposes set forth.

4. In combination with an interlocking mechanism, an electric switch, a lever-bar actuating the same, means for effecting the 55 movement of one member of said interlocking mechanism by the movement of said lever-bar, locking the other connected member of said interlocking mechanism, a bar pivoted to said lever-bar, a bar pivoted to 60 said switch, a solenoid energized by the indication-current of the system, an armature actuated by said solenoid, beveled notches

in said bar pivoted to said lever-bar which engage over said armature, a lug on said bar engaging in a notch in said bar pivoted to 70 said switch, said bars being normally out of engagement and thrown into engagement by carrying a full part of said bar having said beveled notches over said armature, a stop 75 engaging said bar pivoted to said switch preventing the final movement of the lever-bar until released from said switch, said bars being finally thrown out of engagement by said solenoid carrying said armature under one of said beveled notches, permitting the final 80 throw of said lever-bar, and means for producing the final movement of said member of said interlocking mechanism by the final throw of said lever-bar, substantially as and for the purposes set forth.

5. In combination with an electric switch and an interlocking mechanism, of a lever-bar actuating said switch and actuating a member of said interlocking mechanism to lock all conflicting switches and signals by 90 the initial movement of said lever-bar, a bar pivoted to said switch, a bar pivoted to said lever-bar, a solenoid energized by the indication-current, an armature engaging said bar pivoted to said lever-bar, beveled notches 95 in said bar taking over said armature, and having a lug capable of engagement in a notch in said bar pivoted to said switch, said levers being normally out of engagement, and thrown into engagement by the initial 100 movement of the lever-bar carrying said bar pivoted thereto so that the armature engages a full part of said bar, means for preventing the final movement of the lever-bar while in engagement with said switch, means for preventing disengagement with said switch in 105 the case of a false indication, and means for carrying said member of said interlocking mechanism to a final position by the final movement of said lever-bar after the same 110 has been released by the action of the solenoid under the indication-current, substantially as and for the purposes set forth.

6. In combination with an electric switch and an interlocking mechanism, of a lever-bar actuating said switch and actuating said interlocking mechanism upon the initial movement of said lever-bar to lock all conflicting switches and signals, a bar pivoted to 115 said switch, a bar pivoted to said lever-bar, a double-throw solenoid, an armature reciprocated thereby and engaging said bar pivoted to said lever-bar, beveled notches in said bar taking over said armature and having a lug capable of engagement in a notch in said bar 120 pivoted to said switch, said levers being normally out of engagement and thrown into engagement by the initial movement of the lever-bar in either direction, so that said armature engages a full part of said bar having said beveled notches, means for preventing the final movement of said lever-bar in either direction while in engagement with said switch, and means for carrying said member of said 125 130

interlocking mechanism to a final position in either direction by the final movement of said lever-bar after the same has been released by the action of the solenoid under the indication-current, substantially as and for the purposes set forth.

7. In an interlocking switch and signal system, an interlocking mechanism, an electric switch, a lever-bar controlled in its initial movement by said interlocking mechanism, independent thereof in its intermediate movement, controlled in its final movement by a solenoid energized by an indication-current, and governing said interlocking mechanism in the final movement of said lever-bar, and means for preventing said final movement in case of a failure of indication, substantially as and for the purposes set forth.

8. In an interlocking apparatus for switches and signals, interlocking mechanism, an electric switch, a lever-bar, means for actuating said interlocking mechanism by the movement of said lever-bar, mechanism for controlling the throw of said lever-bar, a solenoid for controlling the action of said mechanism governing the mechanism controlling the throw of said lever-bar, and means for preventing the final movement of said lever-bar in case of a failure of indication, substantially as and for the purposes set forth.

9. The combination of an electric switch and a lever-bar actuating the same, of a bar pivoted to said switch, a bar pivoted to said lever-bar actuating said switch, means for throwing said bar so pivoted in and out of engagement, consisting of a solenoid and an armature actuated thereby, and means for preventing the final throw of said lever-bar in case of a failure of indication consisting of a pawl pivoted to the bar pivoted to said lever-bar and arranged to engage the armature of said solenoid and throw the same to the position which prevents the final throw of said lever-bar, substantially as and for the purposes set forth.

10. In an electric switch and signal apparatus the combination with an electric switch or signal, a lever-bar which actuates the same, a solenoid and its armature of means for controlling the apparatus comprising a bar pivoted to said switch and provided with a notch on its lower side, a bar pivoted to said lever-bar which takes over the upper end of said armature and is provided on one side with a lug adapted to engage with said notch and on the other so notched that said armature when actuated by the current will throw said lug in and out of engagement with the first-mentioned notch whereby the switch or signal is

locked and released and the armature being subject to but slight friction is easily actuated by the current, substantially as and for the purposes set forth.

11. In an electric switch and signal apparatus the combination with an electric switch or signal, a lever-bar which actuates the same, a solenoid and its armature of means for controlling the apparatus comprising a bar pivoted to said switch and provided with a notch on its lower side, a bar pivoted to said lever-bar, which takes over the upper end of said armature and is provided on one side with a lug adapted to engage with said notch, and on the other side so notched that said armature when actuated by the current will throw said lug in and out of engagement with said first-mentioned notch, a pawl pivoted at one side of the notched portion of the last-mentioned bar and provided on the upper portion of one end with a shouldered lug adapted to engage with and be thrown by a lug secured to the casing of the switch-lever and adapted at its other end to engage with a lug on the armature whereby the armature is locked in its position and a failure of indication is prevented, substantially as and for the purposes set forth.

12. In an electric switch and signal apparatus, the combination with an electric switch or signal, a lever-bar which actuates the same, and a solenoid and its armature of means for controlling the apparatus comprising a bar pivoted to said switch and provided with a notch on its lower side, a bar pivoted to said lever-bar which takes over the upper end of said armature, and is provided on one side with a lug adapted to engage with said notch and on the other side so notched that said armature when actuated by the current will throw said lug in and out of engagement with the first-mentioned notch, a V-shaped head on the lower end of the armature, a bolt having an oppositely V-shaped head, a chamber in which said bolt is adapted to move, a spring contained within said chamber between the head of said bolt and the bottom of said chamber whereby the bolt is pressed against the armature and when it is suddenly thrown by the actuating-current this pressure is sufficient to prevent a rebound of the armature and a consequent failure of indication, substantially as and for the purposes set forth.

In witness whereof I have hereunto set my hand in the presence of two witnesses.

JOHN D. TAYLOR.
